United States Patent Office

Des. 181,012
Patented Sept. 17, 1957

181,012

ELECTRICALLY POWERED CAN OPENER

Alfred W. Madl, Milwaukee, Wis., assignor to The John Oster Manufacturing Co., Milwaukee, Wis., a corporation of Wisconsin

Application November 16, 1956, Serial No. 43,794

Term of patent 14 years

(Cl. D22—2)

FIG. 1.

Des. 181,012

PAGE 2

Fig. 2.

Des. 181,012

PAGE 3

Fig. 3.

Fig. 4.

Figure 1 is a perspective view of an electrically powered can opener embodying my new design, viewing the same from the top, front and one side thereof;

Figure 2 is a perspective view looking at the front of the electrically powered can opener, viewed substantially at eye level;

Figure 3 is a perspective view of the electrically powered can opener, viewing the same from one side, substantially at eye level; and

Figure 4 is a plan view thereof.

The dominant features of my design reside in those portions thereof shown in full lines.

I claim:

The ornamental design for an electrically powered can opener, as shown and described.
